W. W. FISHER

EAR PHONE HOLDER

Filed June 1, 1927

FIG. 1

FIG. 2

FIG. 3

FIG. 4

INVENTOR
W. W. FISHER

By: Hazard and Miller
ATTORNEYS

UNITED STATES PATENT OFFICE.

WARREN W. FISHER, OF LOS ANGELES, CALIFORNIA.

EAR-PHONE HOLDER.

Application filed June 1, 1927. Serial No. 195,750.

This invention relates to supports, and more particularly to an ear phone holder for use by operators and the like, and toward this end the invention contemplates a simple, 5 practical and effective device for supporting a telephone receiver in horizontal position adjacent the ear of the user.

A still further object of the invention is to provide a device which is simple in its 10 construction, effective in its operation, inexpensive to manufacture, and adequately performs its required function.

With these and many other objects in view which will more readily appear as the nature 15 of the invention is better understood, the same consists in the novel construction, combination and arrangement of parts, which will hereinafter be more fully described, illustrated, and claimed.

20 The essential features of the invention involved in the carrying out of the objects indicated are susceptible to modification; but a preferred embodiment of the invention is shown in the accompanying drawings, in 25 which:

Figure 1 is a side view of the device showing the same in actual operation.

Fig. 2 is a sectional view taken laterally through the device.

30 Fig. 3 is a fragmentary front elevation of the device.

Fig. 4 is a top plan view of the same.

The various figures described above wherein like characters of reference designate like parts throughout, adequately illustrate my invention, and the following detailed description is commensurate with the above mentioned drawings in enabling an artisan to construct and assemble the constituent 40 parts of the same.

The device involves in its general organization a base plate 10 having an elevation 11 thereon, through which elevation a tubular member 13 is counter-sunk as at 12. A second tubular member 14 is collapsible upon the tubular member 13. A vertical slot 15 is formed in the tubular member 13, and a finger button 16 extends through the tubular member 14 and through the slot 15, and is attached within the tubular member 13 to a leaf-spring 18. The leaf-spring has a

bearing surface 19 which bears against the side of the tubular member 13 and is riveted as at 19 to the member 14, and the rivet whereby it is attached, extends through the 55 slot 15. The upper end of the member 14 is flared as at 20 and is trapezoidal in shape. Cut-away portions are formed on opposed sides, which cut-away portions are rounded to conform to the shape of a telephone receiver. These cut-away portions are designated at 22. As will be noticed in Figs. 2 and 3, the outer end of the cut away portion 22 is larger, as at 23, diminishing toward the rear 24, so that when a telephone receiver T 65 is in position it will lie horizontal.

The above description adequately defines my invention in such a manner as to enable an artisan to construct the same.

In actual operation the device may be 70 placed on the table or the like, and the ear phone is received in the cut-away portions as shown in Figure 1. By pressing on the finger button 16, the bearing surface 19 on the leaf-spring 18 releases its engagement 75 with the side of the tubular member 13, and the device may be adjusted vertically to accommodate the different elevations of the ear. The device permits the operator to have free use of both hands while he is receiving his message, and when he is through speaking, he may again place the receiver on the telephone.

80 From the foregoing, it is thought that the construction, use and many advantages of 85 the herein-described ear phone holder will be readily apparent without further description, and it will also be understood that changes in the form, proportion and minor details of construction may be resorted to 90 without departing from the spirit of the invention or sacrificing any of the advantages thereof.

95 What I claim by this invention and desire to secure by Letters Patent, is:

A telephone stand comprising a base plate, a tubular member extending into said base plate, a slot in said tubular member, a second tubular member receivable slidably over said first mentioned tubular member, a leaf-spring, means extending through said slot attaching said leaf-spring to said second 100

tubular member, said leaf-spring bearing against said first tubular member, means extending through said slot providing a finger button for causing said leaf-spring to release 5 its engagement with said first tubular member, whereby said second tubular member is adjustable on said first tubular member, a

flared end on said second tubular member, and opposed cut-away portions on said flared end.

In testimony whereof I have signed my name to this specification.

WARREN W. FISHER.
